UNITED STATES PATENT OFFICE.

EDWARD F. NIEDECKEN, OF MILWAUKEE, WISCONSIN, ASSIGNOR TO HOFFMAN & BILLINGS MFG. CO., OF MILWAUKEE, WISCONSIN.

OPERATING DEVICE FOR WASTE PLUGS.

Application filed April 8, 1927. Serial No. 181,912.

This invention relates to a waste plug operating device especially designed for use with built in bath tubs or the like, although also adapted for other uses.

5 The object of the invention is to provide an operating device of this character which is so compactly organized as to permit of the use of a simplified pipe arrangement, the waste operating mechanism, by virtue of the 10 small space which it occupies, providing the clearance and space necessary for the pipes of the simplified piping arrangement.

Another important object of the invention is to provide a waste operating device of 15 this character which is positively stopped and maintained in either of its two positions and yet is easy and smooth in operation.

Another object is to provide a waste operating device having these advantages and 20 capacities and which is simple and durable in construction, reliable in operation, adjustable and adaptable to various installations, and easy and comparatively inexpensive to manufacture.

25 Other objects and advantages reside in certain novel features of the construction, arrangement and combination of parts which will be hereinafter more fully described and particularly pointed out in the 30 appended claims, reference being had to the accompanying drawings forming a part of this specification, and in which:

Figure 1 is a fragmentary plan view of an 35 installation employing a waste operating device embodying the present invention.

Figure 2 is a fragmentary view in rear elevation of the installation shown in Figure 1.

Figure 3 is a sectional view of line 3—3 40 of Figure 2.

Figure 4 is a view partly in elevation and partly in section taken on line 4—4 of Figure 2.

Figure 5 is a sectional view taken on line 45 5—5 of Figure 4.

Figure 6 is a sectional view taken on line 6—6 of Figure 4.

Figure 7 is a detail view in elevation of the crank arm and its pin; and

50 Figure 8 is a detail view in elevation of the guide.

Referring to the drawings, the numeral 1 designates the studding of the building

structure and the numeral 2 the plaster or tiling thereof. In accordance with the 55 usual practice a steel plate 3 is fastened as at 4 to the studding, the steel plate serving as a support for the waste operating device and the valves.

In the usual built-in tub installation a hot 60 water valve 5 and a cold water valve 6 are provided, the valves 5 and 6 being embodied in the hot water pipe 7 and cold water pipe 8 respectively. In between the valves 5 and 6 the waste operating device designated generally at 9 is provided. Due to the inter-positioning of this waste operating device 65 9 the problem of conveying the hot and cold water to the faucet 10 has been the occasion of some difficulty and annoyance. The simplest method is to provide a cross pipe 11 70 between the outlets of the hot and cold water valves and connect this cross pipe 11 with a single pipe 12 leading to the faucet 10. In all previous installations the waste 75 operating device 9 occupied so much space that it was necessary to curve this pipe 11 above and around the waste operating device in order to clear the same. The curving of the pipe is expensive and difficult and in some installations two pipes have been employed for each of the pipes 11 and 12 to avoid the expense and annoyance of providing a curved pipe although this resulted in a complicated piping system, undesirable 80 for a number of reasons.

As clearly shown in Figures 1 and 2 of applicant's invention, a single ordinary straight pipe 11 need be employed as the waste operating device is so compact as to 85 permit this to be done.

The waste operating device 9 comprises a rotatable or oscillatable shaft 15 mounted in a bushing 16. The bushing 16 has a shoulder 17 adjacent one end and abutting the 95 steel supporting bar 3, and beyond the shoulder 17 the bushing 16 is externally threaded as at 18 and passes through an opening 3^a provided in the supporting-plate 3. The threaded portion 18 of the bushing 100 is engaged with a threaded opening formed in a guide bar 19 having a lug 20 engaged beneath the lower edge of the supporting plate 3. By threading the bushing into the threaded opening of the guide bar, the 105 guide bar and flange 17 of the bushing

clamp the supporting plate 3 between them and, as a result, both the bushing and the guide bar are held in fixed position on the supporting plate.

5 The bushing 16 also serves as a support for an escutcheon 21 which is clamped in position by means of the flanged cap 22 connected to the bushing 16 by coupling sleeve 23.

10 At its outer end the shaft 15 is provided with a knob or handle 24 whereby it may be turned or oscillated. This shaft 15 is free to turn or oscillate but it is held against axial displacement by means of a pin 25 which passes through an opening 26 provided therefor in the bushing 16 and which has a portion positioned in an annular groove 27 formed in the shaft 15 as clearly illustrated in Figures 4 and 5.

20 The inner end of the shaft 15 is formed with reduced extensions 28 and 29 which project beyond the bushing 16. A crank arm 30 is fixed on the reduced extension 28 of the shaft 15 and at its outer end it is formed with a rearwardly projecting crank pin 31 which operates in a cross slot 32 of a slotted head 33 integrally formed with the upper end of a lift bar 34. This head 33 also has a vertical guide slot 35 which extends downwardly from the cross slot 32 at a point adjacent but spaced from one end of the cross slot 32. The guide slot 35 receives the reduced extension 29 of the shaft 15, the reduced extension 29 coacting with the slot 35 to aid in constraining the lift bar 34 to vertical movement. A washer 36 and pin 37 are employed to prevent displacement of the slotted head 33 off of the reduced extension 29. The lift bar 34 ex-

40 tends down through an apertured guide lug 38 integrally formed with the lower end of the guide bar 19. After assembly the lift bar is bent to provide a horizontally extending connecting portion 39. On this portion 39 an eye 40 of a connecting socket 41 is loosely fitted, the eye 40 permitting the socket 41 to be adjusted back and forth on the bar 39 as may be necessary for the particular installation, a pin 42 preventing displacement of the socket 41 entirely off of the connecting portion 39 of the lift bar. A connecting rod 43 has its upper end threaded into the socket 41, a nut 44 locking the connecting rod 43 in its adjusted position in the socket 41. This connecting rod 43 ex-

50 tends down through a stand pipe 44 and at its lower end is connected in any suitable manner to the waste plug (not shown). The stand pipe is held in position by a brace 45 having a clamping portion 46 encircling the stand pipe 44 and clamped thereto by a clamping bolt and nut 47. This brace 45 has an arm 48 which passes through slots 49 provided therefor in a U-shaped clamp 50.

60 The clamp 50 embraces the pipe 7 and is

fastened thereto by set screw 51 which is threaded through the body portion of the clamp 50 and bears the pipe 7. This so pulls the clamp 50 as to cause the arm 48 of the brace to have clamping engagement 70 with the pipe 7 and with the walls of the slots 49 thereby locking the parts in position. A secure and rigid lock is had and yet the brace is vertically, angularly and longitudinally adjustable. 75

When the shaft 15 is turned to swing the crank pin 31 to the left, as viewed in Figure 2, the slotted head 33 and consequently the lift bar 34 and connecting rod 43 and the waste plug are lowered to permit the waste 80 plug to close the waste outlet of the bath tub. When the waste plug is in proper position the pin 31 engages the end wall 32^a of the slot 32, this end wall affording a positive stop of the parts. To raise the 85 waste plug and permit the water to discharge through the drain opening of the bath tub the shaft 15 is turned to swing the crank pin 31 to the right as viewed in Figure 2. This raises the slotted head 33, 90 the lift bar 34 and the connecting rod 43 and when the crank pin 31 has been swung as far as it may be it engages the end wall 32^b of the slot 33, the end wall 32^b also serving as a positive stop for the parts and 95 maintaining the drain plug in open position. In both positions of the crank pin 31 it is past dead center and so related to the dead center position that the weight of the slotted head, of the lift bar and of the connecting 100 rod, et cetera, tends to maintain it in its adjustment.

It is to be noted that the pin 31 engages the upper wall of the cross slot 32 and thus coacts with the upper cross member 33^c of the slotted head 33 when raising the head 33 and connected parts and that it acts in a similar manner though moving in an opposite direction when controlling lowering movement. However, by having the end 110 walls 32^a and 32^b of the end members 33^a and 33^b engageable with the crank pin 31 in its extreme positions, the head has self contained positive stops. The head 33 is offset more on one side than the other from the vertical axis of the lift bar 34 (which vertical axis intersects the center line produced of the shaft 15) and the arrangement is such that the crank pin 31 swings through a quarter of a turn, that is from a position just beyond the vertical or dead center position to a position just above a horizontal position, the extent of the slot 32 being such in relation to the radius of swing of the crank pin that the crank pin has binding 125 engagement with the end walls of the slot in either extreme position.

With these features of smooth and easy operation and positive stopping in either extreme position there is present the further 130

advantage of the compact organization which permits the use of the ordinary straight cross pipe 11. Moreover, the parts may be cast and utilized without machining operations. Finally, the device is adjustable in an easy and effective manner whereby to permit it to be used with any installation.

The compact organization which permits the use of the straight cross pipe is made possible by virtue of the flat structure of the lifting bar and its lift head and also of the guide and crank arm. Notwithstanding this flat construction and the relatively slight depth of the assembly, that is, the relatively slight extent of the assembly, in the direction of the axis of the shaft 15, an extremely strong and durable construction is had and the organization is such that it is not liable to get out of order.

The invention claimed is:

1. An operating device for waste plugs comprising a swingable actuating element, a vertically movable lift bar biased to its lower position and having a cross member beneath which the swingable actuating element engages to effect lifting and to control lowering of the lift bar, and stops at the ends of the cross member and located at different distances from the axis of swing to constrain said swingable actuating element to back and forth swinging movement through substantially a quarter turn and serving to positively stop and releasably hold the swingable actuating element in either of its extreme positions under the influence of the bias of the lift bar.

2. An operating device for waste plugs and the like comprising a swingable actuating element, a vertically movable lift bar biased to its lower position and having a cross member beneath which the swingable actuating element engages to effect lifting and lowering of the lift bar, said cross member having end members engaging the actuating element under the influence of the bias of the lift bar to afford positive stops for the swingable actuating element in either of its extreme positions.

3. An operating device for waste plugs and the like comprising a swingable actuating element, a vertically movable lift bar having a cross member beneath which the swingable actuating element engages to effect lifting and to control lowering of the lift bar, and means for positively stopping the swingable actuating element in either of its extreme positions.

4. An operating device for waste plugs comprising a shaft, a crank fixed to the shaft and having a crank pin, a vertically movable lift bar biased to its lower position and having a head formed with a cross slot extending unequal distances beyond the vertical center line of the lift bar and receiving the

pin, the ends of the cross slot providing positive stops for the pin to limit the up and down movements of the lift bar device and means connected with the lift bar and adapted to be connected with the waste plug.

5. An operating device for waste plugs comprising an oscillating shaft, a hand actuated operating member fixed to said shaft, a crank arm also fixed to the shaft, a crank pin carried by the crank arm, a vertically movable lift bar biased to its lower position and having a head provided with a cross slot receiving the crank pin, the crank pin engaging the upper wall of the cross slot to effect raising of the lift bar and to control the lowering thereof, the end portions of the walls of said cross slot being positioned to engage the crank pin to provide positive stops, means for constraining the lift bar to rectilinear vertical movement, and means connected to the lift bar and adapted to be connected to a waste plug.

6. An operating device for waste plugs comprising a crank pin, a vertically movable lift bar biased to its lower position and having a head provided with a cross slot receiving said crank pin, said cross slot having portions of its wall presenting stops to limit movement of the crank pin in either direction, the crank pin being beyond dead center position when engaged with either stop and being releasably held engaged with either stop by virtue of the bias of the lift bar.

7. An operating device for waste plugs comprising a hand oscillated shaft, a vertically movable lift bar, cooperating means between the shaft and the lift bar for raising and lowering the lift bar as the shaft is turned back and forth, said lift bar having a horizontally extending portion, and a connecting member loosely mounted on said horizontally extended portion for free adjustment therealong and adapted to be connected to a waste plug.

8. An operating device for waste plugs of the type having an oscillating shaft and a lift bar actuated from the shaft and including a supporting member provided with an opening, a bearing for the shaft having a threaded portion projecting through the opening and having a flange engaging the supported member around the opening, and a guide for the lift bar engaged with the threaded portion of the bearing and with the supporting member and also having a lug engaging the supporting member.

9. An operating device for waste plugs comprising a hand operated oscillatory shaft, a crank fixed to the shaft and having a crank pin, a vertically movable lift bar biased to its lower position and having a head formed with a cross slot extending for a substantial distance beyond one side of the vertical center line of the lift bar and extending only slightly beyond the other side

of the vertical center line of the lift bar, the crank pin being fitted in said slot, the ends of the slot engaging the crank pin to limit its movements in either direction, the 5 crank pin being beyond dead center when engaged with either end of the slot whereby the bias of the lift bar releasably secures the

parts in either extreme position and means connected with the lift bar and adapted to be connected with the waste plug. 10

In witness whereof, I hereto affix my signature.

EDWARD F. NIEDECKEN.
